FURNITURE FOOT

George W. Reinoehl, Grand Rapids, Mich., assignor to Stow and Davis Furniture Company, Grand Rapids,
Mich., a corporation of Michigan

Application January 9, 1956, Serial No. 39,644

Term of patent 14 years

(Cl. D10—6)

Fig. 1

Fig. 1 is an elevational view of a furniture foot, showing my new design.

Fig. 2 is a sectional view taken along the plane II—II of Fig. 1.

I claim:

The ornamental design for a furniture foot, substantially as shown.
